FILING CABINET

Emma C. Reinheimer, Magnolia, and Earl R.
Davis, Woodbury, N. J.

Application January 18, 1949, Serial No. 296

Term of patent 14 years

(Cl. D33—19)

To all whom it may concern:

Be it known that we, Emma C. Reinheimer and Earl R. Davis, being citizens of the United States of America, residing in Magnolia, Camden County, New Jersey, and Woodbury, Gloucester County, New Jersey, respectively, have invented a new, original, and ornamental Design for Filing Cabinets, of which the following is a specification, reference being had to the accompanying drawing, constituting a part hereof.

Fig. 1 is a perspective of a filing cabinet, showing our new design with the cabinet doors all closed;

Fig. 2 is a perspective of the same, with the bottom door open;

Fig. 3 is a perspective of the same, with the two top doors open and the lid raised.

The characteristic features of our design reside in those portions shown in solid lines.

We claim:

The ornamental design for a filing cabinet, substantially as shown and described.

EMMA C. REINHEIMER.
EARL R. DAVIS.
